(57) **CLAIM**

The ornamental design for a toy barbecue grill, as shown and described.

DESCRIPTION

FIG. 1 is a front, right and top perspective view of a toy barbecue grill, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view thereof, shown in an alternative, open configuration of use.

The broken lines shown in the drawings illustrate portions of the toy barbecue grill that form no part of the claimed design.
